UNITED STATES PATENT OFFICE.

SAMUEL H. RANSOM, OF ALBANY, NEW YORK.

DESIGN FOR THE PLATES OF A COOKING-STOVE.

Specification forming part of Design No. 6,730, dated June 24, 1873; application filed April 18, 1873.

To all whom it may concern:

Be it known that I, S. H. RANSOM, of the city and county of Albany and State of New York, have invented a Design for the Plates of a Cook-Stove, of which the following is a specification:

The nature of my design is fully represented in the accompanying engraving, to which reference is made.

A A A represent the center ornaments of smaller doors, the main portion having an irregular form with four hollow sides, in the center of which is a prominent half-sphere. From each of the four sides extends a carved leaf. B represents the center ornament for larger door, the main portion being similar to that above described, but with deep beveled

outside. In the center of this, from a stippled surface, rises a half-sphere, from which toward the top and bottom extend spear-shaped formations. On each side extends a fan-shaped scroll addition. C represents the ornamentation of the outer line of the door-panels, being in imitation of a series of beads intertwined by representations of wire.

The moldings I do not claim.

What I claim as my invention is—

A design for the plates of a cook-stove, substantially in the manner above mentioned.

S. H. RANSOM.
